ATTORNEY

UNITED STATES PATENT OFFICE.

SAMUEL RUBEN, OF NEW YORK, N. Y.

THERMOELECTRIC UNIT.

Application filed December 1, 1922. Serial No. 604,452.

To all whom it may concern:

Be it known that SAMUEL RUBEN, a citizen of the United States of America, residing at New York city, N. Y., has invented 5 new and useful Improvements in Thermo-electric Units, of which the following is a specification.

This invention relates to a means of producing thermo-electric effects, and its object 10 is to produce thermo-electric effects with increased efficiency.

It is known that if heat is applied to one of two dissimilar conductive substances in physical contact, a current will flow in a 15 circuit connecting them, and that the greater the difference in their initial electro-physical characteristics such as their thermo-electric powers, the greater the thermo-electric current derived from a given 20 amount of heat; and that, conversely, a current discharged through the couple yields such thermo-electric effects as heating and cooling.

I have found by experiments with combinations of various metals and metallic 25 compounds, that by arranging galena in combination with two electrodes composed of a material, such as copper, the contacting area with one electrode being in excess 30 of that with the other, and applying heat to the electrode of larger contacting area and shielding the other contacting area, to provide for minimum counter thermo-electric effects, very high thermo-electric effects are 35 yielded. Highly satisfactory results were obtained when galena was cast in contact with two copper electrodes, and also when copper electrodes were electro-deposited upon a galena body of proper form, in this way 40 securing maximum contact over areas of given magnitudes.

A form especially adapted to the production of cooling effects, consists of galena cast between and in contact with two concentric copper cylinders. When a current is 45 flowing between the terminal electrodes and the galena, charging the outer electrode positively, two effects are produced, one of cooling, at the outer or active electrode, and one 50 of heating, at the inner or inactive electrode, which latter effect is partially counteracted by the extraction of heat units by a cooling fluid discharged through the inner electrode. By the establishment of greater 55 temperature difference between the two elec-

trodes, the cooling fluid also aids in the production of thermo-electric current. For higher temperatures, iron oxide Fe_3O_4 , cast into form, as the conductive compound, is preferable to galena because of its higher 60 melting point.

The principles of the invention can best be further explained in connection with certain illustrative embodiments of the invention shown in the accompanying drawings, in which,

Fig. 1 represents the thermo-electric unit composed of a galena rod cast within a cylindrical copper electrode and about copper electrodes, one at each end, a part of the 70 unit being shown in section.

Fig. 2 represents another form of the thermo-electric unit in which a part of the unit is shown in section.

In Fig. 1, 1 represents a galena body cast 75 in contact with two copper terminals 2, and within copper cylinder 3; 4, 5 and 6 being binding posts in a circuit having terminals at 7.

In Fig. 2 is shown a galena cylinder cast 80 between two concentric copper cylinders 3 and 8.

Employing the units shown in Figs. 1 and 2 as generators of thermo-electric current, as heating energy is applied to copper coating 3, electro-physical reactions occur between the electronic systems of copper electrodes 3 and 8 and those of galena body 1, resulting in a thermo-electric current to a circuit from terminals at 7. When the device shown in Fig. 2 is so employed, a cooling fluid, such as a stream of water or air, can be discharged through the inner electrode 8, which establishes a greater temperature difference between electrode 3, and electrode 8, thus serving to increase the production of current. Employed in the production of cooling effects, the outer cylinder 3, is positively charged, when the galena is negative to it, and the cooling fluid prevents a 100 temperature rise between the galena and the inner electrode, due to polarity effects; the fluid also assists in extracting some of the resistance heat loss.

What I claim is,

1. A thermo-electric unit composed of an electrically conductive crystalline compound in molecular contact with two opposing electrodes, so arranged with respect to said compound that the contact area between one 110

electrode and said compound is greater than the contact area between said compound and said other electrode.

2. A thermo-electric unit comprising two electrically conducting cylinders coaxially arranged one within the other, and adapted to be connected as opposing electrodes in an electric circuit, the adjacent surfaces of said cylinders being in molecular contact with an electrically conducting crystalline compound within the space therebetween.
3. A thermo-electric unit comprising two electrically conducting cylinders arranged

coaxially one within the other, and adapted to be connected as opposing electrodes in an electric circuit, the adjacent surfaces of said cylinders being in molecular contact with an electrically conducting crystalline compound within the space therebetween, and adapted for the discharge of a cooling fluid in contact with the inner surface of said cylinder of the smaller diameter.

In testimony whereof, SAMUEL RUBEN has signed his name to this specification.

SAMUEL RUBEN.
